UNITED STATES PATENT OFFICE.

CHARLES A. HAMLIN, OF GREENBUSH, ASSIGNOR TO THE RANSOM STOVE COMPANY, OF ALBANY, NEW YORK.

STOVE.

SPECIFICATION forming part of Letters Patent No. 292,805, dated February 5, 1884.

Application filed May 1, 1883. (No model.)

To all whom it may concern:

Be it known that I, CHARLES A. HAMLIN, of Greenbush, in the county of Rensselaer and State of New York, have invented certain new 5 and useful Improvements in Stoves for Burning Bituminous Coal, of which the following is a specification.

My invention relates to improvements on the stove for burning bituminous coal for which 10 Letters Patent No. 231,163 of the United States were granted to me on the 17th day of August, 1880; and the object of these present improvements is to simplify the construction of the stove, make its operation more effective, and 15 render its management more simple and easy.

By experimenting I have discovered that the admission of air at the forward edge of the imperforate fire-bed, as shown and described in my aforesaid Letters Patent, instead of being 20 beneficial to the effective operation of the stove, is, on the contrary, highly detrimental thereto, for the following reasons: First, the air that enters through the said opening intensifies the combustion at that point and rapidly 25 consumes the coke that lies in close proximity to said opening, thereby quickly converting the coke into fine ashes, that readily escape through the said air-opening and leave an unobstructed passage for the admission of cold 30 air into the flame-chamber, in which the cold air will chill the unconsumed gases that enter from the retorting-chamber and convert said gases into a dense black smoke, and in this manner defeat the object for which the 35 said air-opening was designed; and, second, the aforesaid rapid combustion of the coke at the forward part of the fire-bed produces a corresponding retardation of the combustion at the rear of the retorting-chamber, adjacent 40 to the ingress draft-opening. By my present improvement these defects are remedied, for the reason that all the air that is admitted into the retorting-chamber is compelled to enter to the burning coke through the rear of said retorting-chamber, and as it passes through the rear grate the air becomes highly heated and 45 mingles with the distilled gases that are at the same temperature. The commingled air and gases escape into the flame-chamber in the 50 form of an intensely-heated flame.

To accomplish this end my invention consists in combining with an imperforate fire-bed, that is specially constructed to prevent any admission at its ends and forward edge, an inclined rear grate located beneath the rear 55 part of the retorting-chamber, and a partition-wall between the retorting-chamber and flame-chamber, whose lower edge is disconnected from the fire-bed, to form at a point opposite the rear grate an egress draft-opening, whereby the draft-currents will be forced to pass through the fuel lying upon the imperforate fire-bed in a horizontal direction, as hereinafter described.

In the accompanying drawings, which form 65 part of this specification, and to which reference is made herein, Figure 1 is a vertical section of a stove containing my present improvements, and Fig. 2 a horizontal section of the same at the line *x x*. 70

As represented in the drawings, A is the body of the stove, which I preferably make in a rectangular form, as shown in Fig. 2. The said body contains the retorting-chamber B, combustion-chamber C, and flame-chamber D. 75 The retorting-chamber B is located in the rear portion of the body A, and is inclosed by the non-conducting walls *b* and bridge-wall *b'*, the latter being, from necessity, composed of the best heat-resisting material that I can obtain. 80 The said retorting-chamber is provided with a feeding-door, (indicated by dotted lines in Fig. 1,) through which the bituminous coal is introduced into said chamber. The combustion-chamber C occupies the body of the stove 85 beneath the retorting-chamber B and below the line of the under edge of the bridge-wall *b'*. Said combustion-chamber has at its back part the rear grate, *c*, which I preferably fix in an inclined position, and which forms the inlet 90 air-openings for supplying the air required to furnish oxygen for maintaining the combustion of the coke contained in said combustion-chamber. At the bottom of said chamber an imperforate fire-bed, *c'*, is placed, and the said fire-bed differs from the one shown and described in my former patent hereinbefore referred to in this respect: it has no opening for the admission of air, either at its front edge or ends, for producing an ignition of the 95 100

gases as they escape from the fuel in the retort-chamber B. The said fire-bed, as shown in the drawings, is hinged at its rear side, so that it may be dropped for the purpose of emptying the fuel from the retorting-chamber. A fastening device, c^2 , is arranged at the front side of said fire-bed for the purpose of holding it up in place, as shown in the drawings; but I do not confine myself to this particular arrangement, for the reason that any imperforate fire-bed that will exclude the air from entering the combustion-chamber at the front side and ends of said fire-bed will serve the same purpose equally as well. The flame-chamber D is separated from the retorting-chamber B by means of the bridge-wall b' . The space below the lower edge of said bridge-wall constitutes the egress draft-opening d , which is located directly opposite to the ingress draft-openings through the rear grate, c . Through the egress draft-opening d the gases that are eliminated from the crude fuel in the retorting-chamber, which gases become commingled with the excess of air that has entered into the combustion-chamber through the inlet draft-openings, escapes, in a highly heated condition, into the flame-chamber D, wherein they become ignited and burn with great intensity. The unconsumed gases from the flame-chamber D escape through the outlet E, and are carried away therefrom by means of the usual escape-pipe. A door, F, at the rear of the body of the stove affords the means for reaching the grate c , for the purpose of agitating the fuel, and for removing any débris from the fire-bed c' through an opening, c^3 , formed at the base of the grate c . Air for supplying the oxygen required for supporting combustion is admitted into the ash-pit G through a registered opening, g , in the front door, g' , and after its admission into said ash-pit the air follows the course indicated by the arrows marked on Fig.

1. A mica door, H, in the front of the flame-chamber D, affords the means for securing a pleasant illumination from the burning gases in said flame-chamber. It will be seen that in this improved form of my stove the draft-currents are at all times forced to pass through the combustion-chamber C in a horizontal direction from the ingress draft-openings to, and out of the egress draft-opening d , as no provision is made for a direct or alternative draft. The heat rising from the combustion-chamber C is sufficient to distill the gases from the bituminous coal contained in the retorting-chamber B, and to convert the said coal into an incrustation of coke, which is continually burned away from its under side by reason of the enforced horizontal draft-currents until said coke is reduced to ashes, which are removed from the bottom of the combustion-chamber through the opening c^2 . Fresh incrustations of coke are being constantly formed by distilling the gases from the coal in the retorting-chamber B, to take the place of the coke consumed by the fire in the combustion-chamber C.

I claim as my invention—

The combination, with a retorting-chamber, B, a combustion-chamber, C, lying directly underneath said retorting-chamber, and a flame-chamber, D, separated from said retorting-chamber by means of the bridge-wall b' , whereby the egress draft-opening d is formed, as herein described, of the inclined rear grate, c , fixed under the retorting-chamber B, and the imperforate fire-bed c' , arranged to form a close joint with the combustion-chamber C at the ends and one side of said chamber, as and for the purpose herein specified.

CHARLES A. HAMILIN.
